CONTROL SYSTEM

Igor E. Grosdoff, Princeton, N. J., assignor to
 Radio Corporation of America, a corporation of
 Delaware

Application April 5, 1946, Serial No. 659,704

2 Claims. (Cl. 250—27)

1

This invention relates to control systems such as are adapted (1) to limit industrial processes to a selected interval of time, (2) to control a device for delivering a selected number of articles to be enclosed in a container or package, or (3) to exert a control effect generally in cases where it is desired to count or measure quantities such as periods of time, numbers of objects, or the like.

In many processes such as spot welding and chemical reactions it is desirable to have available a stop watch type of apparatus which may be utilized to terminate the process at the end of a predetermined interval of time. In other processes such as the bottling or packaging of articles, it is desirable to have available means whereby selected numbers of such articles may be delivered to the containers in which they are to be sold. To avoid wear and waste of energy, it is sometimes desirable that the counting and measuring apparatus cease to operate when the controlled process is completed.

In accordance with the present invention, these results are achieved by means of a control system which includes a plurality of trigger circuits connected in groups each of which (1) is arranged to register a count of ten, and (2) is provided with means whereby any count of the group may be selected for the purpose of exerting a control effect. These different groups or decades are connected together so that one negative pulse is delivered from a lower decade to the next higher decade each time such lower decade completes its cycle of ten. Thus if 0.01 second is required to complete the cycle of the first or lowest decade, the cycle of the second decade will be completed in 0.1 second and that of the third decade will be completed in 1.0 second.

The trigger circuits of the different decades are of the type including a pair of triodes each of which (1) has its anode coupled to the grid of the other through a resistor shunted by a capacitor, (2) has its cathode grounded, (3) has bias potential applied to its grid through a separate resistor, and (4) has operating potential applied to its anode either through a separate resistor or through a separate resistor and a resistor which is common to the anodes of the two electron discharge devices. Under these conditions, only one of the triodes conducts current at a time, and current conduction is transferred from one of the triodes to the other in response (1) to the application of a negative pulse to the grid of a triode which is conducting current, (2) to the

application of a positive pulse to the grid of a triode which is not conducting current, or (3) to the application of a negative pulse to the common anode terminal of a trigger circuit having a resistor common to both its anodes. In all cases, the control pulses are applied to the input terminal of the lowest decade.

The selector for producing a desired control effect in response to different numbers of pulses applied to the input terminal of the lowest decade may be either in the form of a separate selector switch for each decade or in the form of a single selector switch for all the decades. In either case, (1) the application of pulses is started by completion of a circuit between the source of pulses and the input of the lowest decade, and (2) this circuit is interrupted and a control pulse is applied to the controlled device when a number of input pulses predetermined by the setting of the selector switch or switches has been applied to the input terminal of the lowest decade.

The principal object of the invention is the provision of an improved control system and method of operation whereby a control pulse is produced in response to any desired number of input pulses. Important objects of the invention are the provision of a control system which is adapted to limit an operation to a selected time interval, and the provision of a control system which is adapted to respond to a selected number of pulses for producing a measuring or counting effect.

The invention will be better understood from the following description considered in connection with the accompanying drawings and its scope is indicated by the appended claims.

Referring to the drawings:

Fig. 1 is a wiring diagram of the control circuits of one form of the invention, the counters or decades being shown as blocks bearing a switch blade and fixed contacts numbered 9 to 9.

Fig. 2 is a wiring diagram of one form of counter or decade.

Fig. 3 illustrated a modified form of control circuit, and

Fig. 4 is a wiring diagram of a preferred form of the invention which has the advantage that it is simpler and involves fewer parts than the modifications of Figs. 1 to 3.

The computer of Fig. 1 is shown as including three chains of multi-vibrators or trigger circuits 20, 21 and 22. These chains are designed in manner well known in the art so that the chain 22 completes its cycle in 0.01 second, the

chain 21 completes its cycle in 0.1 second and the chain 20 completes its cycle in 1.0 second. As a result, each multivibrator unit of the chain or decade 22 represents 0.001 and those of the decades 21 and 20 represent respectively 0.01 second and 0.1 second. These decades are so interconnected that each time a lower decade completes its cycle, it delivers one pulse to the input terminal of the next higher decade. For example, the three decades of Fig. 1 are capable of measuring a time interval of 1.000 second or any shorter time interval down to 0.001 second. This type of time computing device is well known and readily understood without detailed explanation.

The present invention relates to the use of such a computer to select or indicate different intervals of time dependent on the setting of the computer. To this end, a switch 23 is provided for starting and stopping the time measuring operation, the stopping of the operation being effected through a multigrid tube 24 having grids 25, 26 and 27, a cathode 28, and an anode 29 connected to a positive terminal through a resistor 30.

Associated with the decade 22 is a lead 31 which is coupled through a capacitor 32 to the grid 27 and is connected to a switch blade which is arranged to engage fixed contacts 0, 1, 2, 3, 4, 5, 6, 7, 8 and 9 for connecting the lead 31 to any one of the multivibrator units of the chain or decade 22. If the blade is in engagement with the fixed contact 7, a positive pulse is applied to the grid 27 each time a count is registered on the corresponding multivibrator of the decade. Similarly the decades 21 and 20 are provided respectively with leads 33 and 35 and with fixed switch contacts numbered in the same manner as those of the decade 22, the lead 33 being connected through a resistor 34 to the grid 25 and the lead 35 being connected through a resistor 36 to the grid 26.

The tube 24 takes current only when all three of its grids are made more positive. This can be made to occur in response to the application of any desired number of pulses to the decades 20-21-22. For example, closure of the switch 7 of decade 22, the switch 6 of decade 21 and the switch 5 of decade 20 means that all three grids will be positive only at a period of 0.567 second after the time measuring operation is started. At the end of this period, the tube 24 draws current through a resistor 30 thereby producing a negative pulse at the grid 36 of the switch 23 and operating this switch to interrupt the application of input pulses from a source 38 through a control tube 39 to the input of the decade 22.

The switch 23 includes a pair of trigger circuits 49 and 41, and a duotriode 42 which (1) is provided with a resistor 43 common to its two anodes and (2) has its anodes connected through a resistor 44 to the first control grid 45 of the control tube 39. Bias potential is applied from a lead 46 through resistors 47 and 48 respectively to the left hand grids 49 and 50 of the trigger circuits 40 and 41, and from the lead 46 through a reset switch 51 and resistors 52 and 53 respectively to the right hand grids 54 and 55 of the trigger circuits 40 and 41. Opening and closing the switch 51 puts the trigger circuit units 40 and 41 in a standby condition with current conduction in their right hand anodes as indicated by the arrows. Under these conditions, the grid 55 of the duotriode 42 is more positive, the grid 56 of the duotriode 42 is more negative, and sufficient current flows in

the resistor 43 to maintain the grid 45 of the control tube 39 at such a potential that no pulses are supplied from the source 38 through the control tube 39 to the decade 22.

The supply of pulses to the decade 22 is started by closing and opening switch 57 which functions to transfer current conduction to the left hand anode of the unit 40 thereby making the grid 55 more negative, reducing the current of the resistor 43 and applying to the grid 45 a more positive potential such that oscillations are transmitted through the control tube 39 to the decade 22.

With the switch blades of the decades 20, 21 and 22 set as illustrated, the tube 24 is biased off for any number of input pulses less than 567. When the number of input pulses reaches 567, grids 25 and 26 are positive by conduction and a positive pulse is applied to the grid 27 through the capacitor 32. As a result, the tube 24 draws current through the resistor 30, a negative pulse is applied through the lead 37 to the grid 36, current conduction goes to the left hand anode of the unit 41, the grid 56 is made more positive, more current is drawn through the resistor 43, and the potential of the grid 45 is made sufficiently negative to stop the supply of pulses through the control tube 39 to the decade 22.

The decades 20, 21 and 22 of Fig. 1 may be of various types such as (1) that illustrated by Fig. 2 wherein a different trigger circuit is provided for each digit of the decade or (2) those illustrated by Fig. 4 wherein a smaller number of trigger circuits are combined with a resistance network to provide the required digital representation.

For convenience in understanding there is illustrated in Fig. 2 a decade which (1) includes ten trigger circuit units 58 to 67 which are connected through a lead 68 in a closed loop or chain and (2) may be taken as representative of the decades 20, 21 and 22 of Fig. 1.

Operating potential is applied from a terminal 69 to the anodes of the units 58 to 67 through separate resistors 60 to 79, bias potential is applied to their grids from leads 80 and 81 through resistors 82 to 101, and a reset switch 102 is provided for putting the decade in a standby condition with current conduction in the anode resistors 60, 63, 65, 67, 69, 71, 73, 75, 77 and 79. Input pulses are applied to the left hand grids of the various units through a lead 103 and the capacitors 104 to 113. It will be noted that the left hand anodes of the units 58 to 67 are each coupled to the left hand grid of the next successive unit through a capacitor 114 and that the triodes of each unit have their grids and anodes cross-connected as previously explained so that only one triode of the unit conducts current at a time.

The operation of such a decade as this is too well known to require detailed explanation. It is based on the fact that (1) only one of the units 58 to 67 is conducting current through its left hand anode at any given time, (2) all the other units are insensitive to a negative pulse applied through the terminal 103 and the capacitors 104, 105, etc., (3) such a negative pulse functions to transfer current conduction from the left anode to the right anode of the one unit, and (4) there is applied from the left anode of the one unit through a capacitor 114 to the left hand grid of the next successive unit a positive pulse whereby current conduction is transferred from the right to the left anode of this next suc-

cessive unit which is thus made sensitive to the next negative pulse applied from the terminal 103 through the corresponding capacitor to the grid of the conducting triode. This process continues throughout the decade, the cycle of operation being repeated over and over again so long as negative pulses are applied to the terminal 103.

With the setting of the selector switch as illustrated in Fig. 2, a positive pulse is applied through the lead 31 and the capacitor 32 to the grid 27 (see Fig. 1) each time current conduction is transferred from the left to the right anode of the unit 64. Each time the decade 22 completes its cycle of ten counts, a positive pulse is applied through a coupling capacitor 115 to the grid of a triode 116 and a negative pulse is applied from the terminal 117 to the pulse input terminal of the decade 21. The decade 21 is similarly connected to the decade 20. Thus with the three selector switches set as illustrated in Fig. 1, all three grids of the tube 24 are made positive only when current conduction is transferred from the left to the right anode (1) of unit 64 of decade 22, (2) of unit 63 of decade 21, and (3) of unit 62 of decade 20. This corresponds to a count of 567 pulses. It is obvious that any other desired number of pulses may be selected to terminate the supply of pulses and to energize a control device connected to the terminals 119 and 120 of Fig. 1.

The modification of Fig. 3 is similar to that of Figs. 1 and 2 with the exception that different means are provided for applying the stop signal to the switch 23. In this case, the pentode 24 of Fig. 1 is replaced by a triode 121. Grid bias potential for the triode 121 is derived from a resistor 122 which has its high voltage terminal connected to the anodes of diodes 123, 124 and 125. The cathodes of these diodes are connected to the selector switch blades of the decades 22, 21 and 20 respectively.

With the three selector switches in their illustrated positions, all three diodes draw current only when current conduction is in the right hand anodes of the unit 64 of decade 22, the unit 63 of decade 21 and the unit 62 of decade 20. When all three diodes conduct current, the grid of triode 121 becomes sufficiently negative to stop current through the anode resistor 126, and a positive control pulse is delivered to the lead 37 of the stop switch 23 (Fig. 1) and to any other controlled device which may be connected to this lead.

The modification of Fig. 4 is preferable to those previously described for the reason that it involves fewer trigger circuits and is controlled by a less complicated selector mechanism. It is distinguished by the fact that (1) the decades consist of only four trigger circuit units so interconnected that they function to deliver one output pulse in response to ten input pulses, (2) a single selector mechanism is provided for all the decades, and (3) the whole control system operates continuously to deliver a positive output pulse in response to 10 input pulses, 12 input pulses, 25 input pulses, 50 input pulses or 100 input pulses dependent on the setting of this single selector mechanism. The decades of this modification are like those disclosed in my co-pending application Serial No. 580,446, in that they include a feedback connection from the left hand anode of the fourth trigger circuit of the decade to the right hand grid of the second trigger circuit and from the left hand anode of the third trigger circuits to the right hand grid of

the second trigger circuit so that an output pulse is delivered to the next decade only when ten input pulses have been applied.

The control system of Fig. 4 is illustrated as including two decades 128 and 129. The decade 128 includes four trigger circuit units 130 to 133 which are of a well known type having operating potential applied to their anodes from a socket power unit 134 through lead 135, a resistor 136 common to the two anodes of the unit and resistors 137 and 138 which are individual to the separate anodes. Grid bias potential is applied from the socket power unit 134 through leads 139, 140 and 141 and resistors 142 and 143. A reset switch 144 connected between the leads 140 and 141 is opened and closed to put the decade 128 in a standby condition with current conduction in the resistors 138. Negative input pulses are applied through a coupling capacitor 145 to the common anode terminal of the first or lowest order unit 130 of the decade. Such negative input pulses are derived through a switch 146 and a triode 147 which has its anode 148 coupled through a capacitor 149 to the grid 150 of a triode 151 so that the current of the triode 151 is increased in response to each input pulse and a negative pulse is produced at the terminal 152 of the resistor 153.

The decade 129 is similar to the decade 128. In both cases the anode 154 of the lower order unit is coupled through a capacitor 155 to the common anode terminal of the next higher order unit as is usual in counters of this type. The output terminal of the decade 128 is coupled to the input terminal of the decade 129 through a capacitor 158 so that one pulse is delivered to the decade for every ten pulses applied to the input of the decade 128.

The left hand anode of the unit 133 is connected through a feed-back connection 160-161 to the right hand grid of the unit 132 and the left hand anode of the unit 132 is similarly connected to the right hand grid of the unit 131 through a feedback connection 169-169'. The corresponding units of the decade 129 are similarly interconnected. With these connections, each decade of four triodes delivers one output pulse in response to ten input pulses.

Positive output pulses are delivered from the common anode terminal 165 of a pair of triodes 166 and 167 which are connected to the high voltage terminal 135 through a resistor 168. So long as the triodes 166 and 167 take current, the output terminal 156 is more negative. When the current drawn through the resistor 168 decreases, the terminal 156 is made more positive. The amount of current drawn through the resistor 168 is determined by the potential applied to the grids 170 and 171 of the triodes 166 and 167. Such potential is controlled by a selector switch 172 which is connected to the decades 128 and 129 so that minimum current is drawn through the resistor 168 only in response to a count of 10, 12, 25, 50 or 100 input pulses.

The selector 172 includes (1) a conductive segment 173 having a contact 174 which is arranged to engage a plurality of fixed contacts 175 to 178 as segment 173 is rotated around its axis, (2) a conductive segment 179 having a contact 180 arranged to engage a plurality of fixed contacts 181 to 185 as segment 179 is rotated together with the segment 173, and (3) a pair of brush contacts 186 and 187 through which the segments 173 and 179 are connected respectively

to the control grid of the triode 167 and to the grid of the triode 166.

With the selector 172 in its illustrated position, the grids 170 and 171 are both connected to the right hand anode of unit 191 of the decade 129. Since current conduction is transferred to the right hand anode of the unit 191 only in response to each 100 input pulses, it is apparent that a positive pulse will be delivered through the capacitor 192 to the output terminal 156 for each 100 input pulses.

With the selector in a position such that the contact 174 engages the contact 175 and the contact 180 engages the contact 182, (1) a negative potential is applied from the right anode of the unit 133 through contacts 174, 175 and 186 to the grid 170 and (2) a negative potential is applied from the left anode of the unit 190 and the left hand anode of the unit 188 through contacts 182, 180 and 187 to the grid 171. Since this condition of the decades represents a count of 50 input pulses, it follows that a positive pulse is delivered at the terminal 156 for each 50 input pulses.

When the selector 172 is in a position such that the contact 174 engages the contact 176 and the contact 180 engages the contact 183, (1) the grid 170 is connected through contacts 186, 174 and 176 to the left hand anode of the unit 132 and the left hand anode of the unit 130 and is made negative in response to a count of 25 input pulses and (2) the grid 171 is connected through contacts 187, 180 and 183 to the left hand anode of the triode tube unit 189 which is also negative at the count of 25 input pulses. A positive output pulse is therefore delivered at the terminal 156 in response to 25 input pulses.

When the selector 172 is in a position such that the contact 174 engages the contact 171 and the contact 180 engages the contact 184, the grid 170 is connected through contacts 186, 174 and 177 to the left hand anode of the unit 131 and the grid 171 is connected through contacts 187, 180 and 184 to the left hand anode of the unit 188 so that both grids are made negative in response to a count of 12 input pulses and a positive pulse is delivered at the output terminal 156.

When the selector 172 is in a position such that the contact 174 engages the contact 178 and the contact 180 engages the contact 185, the grid 170 is connected through the contacts 186, 174 and 178 to the right hand anode of the unit 133 and the grid 171 is connected through the contacts 187, 180 and 185 to the left anode of the unit 188 so that both grids are made negative in response to ten input pulses and a positive output pulse is delivered at the output terminal 156.

The output pulse delivered at the terminal 156 obviously may be utilized for a variety of purposes such as moving an empty container into a position to receive a counted number of articles or the like. The input pulses applied through the capacitor 145 may be produced by such articles obstructing the light applied to a photoelectric cell as they drop into the container. Other uses for the control system will be apparent to those skilled in the art.

What the invention provides is a control system which may be adjusted to produce a control pulse in response to any one of a number of selected groups of input pulses. Such control

pulses may provide a measure of time, a measure of numbers of articles or the like depending on the use made of the invention.

I claim as my invention:

5 1. The combination of first and second counters each having an input lead and an output lead and each including four trigger circuits so interconnected that its cycle of operation is completed in response to the application of ten pulses to its input lead, means coupling the output lead of said first counter to the input lead of said second counter, unitary switching means connected to said first and second counters to select from said counters pairs of potentials each pair of which is more negative only in response to the application of a different predetermined number of pulses to the input lead of said first counter, and means responsive to each of said pairs of more negative potentials for producing a single output pulse.

15 2. The combination of first and second counters each having an input lead and an output lead and each including four trigger circuits so interconnected that its cycle of operation is completed in response to the application of ten pulses to its input lead, means coupling the output lead of said first counter to the input lead of said second counter, unitary switching means connected to said first and second counters to select from said counters pairs of potentials each pair of which is more negative only in response to the application of a different predetermined number of pulses to the input lead of said first counter, and a pair of triodes having a common anode resistor and having their grids connected to respond to said pairs of potentials for producing a positive output pulse at their common anode terminal.

IGOR E. GROSDOFF.
